UNITED STATES PATENT OFFICE.

JOHN A. RICHTER, OF OSAWATOMIE, KANSAS.

SPARK-ARRESTER.

SPECIFICATION forming part of Letters Patent No. 688,693, dated December 10, 1901.

Application filed November 12, 1900. Serial No. 36,214. (No model.)

To all whom it may concern:

Be it known that I, JOHN A. RICHTER, a citizen of the United States, residing at Osawatomie, Miami county, Kansas, have invented a 5 new and useful Spark-Arrester, of which the following is a specification.

My invention relates to spark-arresters; and my object is to produce a structure of this character for locomotive smoke-stacks in 10 particular whereby chances of firing houses, haystacks, &c., are practically eliminated and a more economic consumption of fuel is attained.

A further object is to produce a spark-arrester which can be applied in a modified form to either the ordinary or the "extension-front-end" locomotive, in the latter case thereby avoiding danger of warping and cracking of the casting by an accumulation 20 of hot cinders; furthermore, to produce a construction which is simple, strong, durable, and cheap.

With these objects in view the invention consists in certain novel and peculiar features of construction and combinations of parts, as hereinafter described and claimed, and in order that it may be fully understood reference is to be had to the accompanying drawings, in which—

30 Figure 1 is a longitudinal section taken on the line IV IV of Fig. 2 and showing what is known as an "extension-front-end" locomotive with a form of arrester therein. Fig. 2 is a section taken on the line V V of Fig. 1.

35 Fig. 3 is a front view showing an attachment for conducting the cinders to the ground at one side of the track instead of returning them to the fire-box or combustion-chamber.

In the said drawings, 1 designates a locomotive, which may be of the ordinary type or may have its front end extended, as shown at 1^a, the latter type being technically referred to as the "extension-front-end" boiler or locomotive, this extension being provided 45 for the purpose of providing space wherein cinders may accumulate, which accumulation is found in practice to warp and crack the casting in a comparatively short time.

2 designates the boiler-tubes, extending 50 from the furnace 3 to the smoke-box 4, with which the smoke-stack 5 communicates. In the bottom of the smoke-box vertically below

the smoke-stack is found the nozzle 6^a to exhaust up through the smoke-stack, thereby creating and maintaining a forced draft to 55 properly support combustion.

17 designates tubular arms branching from nozzle 6^a, and 18^a pipes or tubes connected at their opposite ends to said branch nozzles and the front ends of pipes 13, extending rearwardly and adapted to discharge into the combustion chamber or furnace, the front ends of said pipes being connected to a box 20.

The box 20, above referred to, is of such construction that it forms the communicating 65 passages 21, 22, 23, and 24, passage 21 enveloping the front ends of all of the boiler-tubes and communicating at its lower end with the lower end of passage 22, a slide-plate 25, secured to the diaphragm or partition 26 between passages 21 and 22, serving as a means 70 whereby the draft may be regulated or controlled by increasing or diminishing the width of the throat or opening connecting said passages. That portion of the box comprising 75 passages 22, 23, and 24 is inverted-U shape in side view and is narrower than chamber 21, which extends to the sides of the boiler. The other portion of the box, in which passages 24 are located, is widened, so as to provide 80 passages 27 at opposite sides of passages 24 and communicating therewith through openings 28, and from said openings inclined deflectors 29 and 30 converge upwardly and inwardly at opposite sides of the center of passages 24, so 85 that the draft or blast shall follow the tortuous course down through said passages indicated by the arrows, Fig. 2, and escape into the lower front end of the smoke-box, as indicated clearly in Fig. 1, from whence the 90 draft forced by discharge of steam from the nozzle 6^a up through the smoke-stack carries it up through the latter in the usual manner, but relieved largely of its combustible gases and practically all of the hot coals and cinders, as hereinafter explained, and in this connection it may be stated that for convenience the discharge-nozzle 6^a will project up 95 through passage 23, as shown. The lower ends of passages 27 register with holes 31, 100 formed in the extension-head, and also registering with said holes are the upturned ends of return-pipes 13^a, above referred to. It will thus be seen that tubes 18^a, hereinbefore de-

scribed, extend down through the extension front end and discharge back into return-pipes 13^a, so as to create a suction sufficiently strong to draw the heavy gases and all cinders entering passages 27 back and into the combustion-chamber, these gases and cinders being deflected into said passages, because intercepted by the overlapping ends of the oppositely-projecting deflectors 29 and 30, assuming, of course, that the draft from the nozzle 6^a is not sufficiently heavy to overcome the suction created by the blast from branch pipes 18^a and the weight of the unconsumed or partly-consumed fuel. By this arrangement it is obvious, therefore, that hot cinders cannot accumulate in the extension front end and that danger of the warpage and cracking of the latter is consequently eliminated. Furthermore, the coals and hot cinders being returned to the furnace the operation of the locomotive is more economic and danger of firing adjoining property is eliminated.

In some cases it may be desirable to discharge the hot cinders upon the ground at one side of the track. In this case the return-pipes 13^a are dispensed with and in lieu thereof short pipes 32 are secured to the extension front end and are arranged to receive the cinders from passages 27 and discharge them into a box 33, having a laterally-projecting spout 34, whereby they are discharged at the will of the engineer in the cab at one side of the track. It will be understood, of course, that the spout will be provided with a suitable valve having a flexible connection leading to the cab, this construction not being illustrated, as it may be of any common or preferred type.

From the above description it will be apparent that I have produced a spark-arrester for locomotives and kindred engines which

embodies the features of advantage enumerated as desirable in the statement of invention and which is obviously susceptible of modification in various minor particulars without departing from the spirit and scope of the invention.

Having thus described the invention, what I claim as new, and desire to secure by Letters Patent, is—

1. In a spark-arrester for steam-engines, an arched box having its opposite ends open, and its rear end arranged to receive the products of combustion, and having its front portion provided with two parallel perforated partitions, forming three longitudinal passages, and provided also with deflectors extending inwardly and upwardly of the central passage from the lower margins of the perforations of said partitions, pipes connecting the discharge or lower ends of the side passages with the furnace, and steam-discharge nozzles, projecting rearwardly into said return-pipes, substantially as described.

2. In a spark-arrester for steam-engines, the combination of an arched box having its opposite ends open and its rear end arranged to receive the products of combustion and its front portion divided to provide a plurality of longitudinal passages, said divisions or partitions being provided with openings, and deflectors which extend inwardly and upwardly of the central passage from the lower margins of said openings, and a discharge pipe or tube connected to the passages at opposite ends of said central passage, substantially as described.

In testimony whereof I affix my signature in the presence of two witnesses.

JOHN A. RICHTER.
